(57) **CLAIM**

The ornamental design for a cover for footwear, as shown and described.

DESCRIPTION

FIG. 1 is an upper perspective view of the cover for footwear showing my design with the detachable pads in an assembled configuration.

FIG. 2 is a bottom perspective view of the cover for footwear in the assembled configuration;

FIG. 3 is a lateral side view of the cover for footwear in the assembled configuration;

FIG. 4 is a medial exploded side view of the cover for footwear in a disassembled configuration with broken lines showing unclaimed portions of the cover;

FIG. 5 is a front view of the cover for footwear in the assembled configuration;

FIG. 6 is a rear view of the cover for footwear in the disassembled configuration with broken lines showing unclaimed portions of the cover;

FIG. 7 is a top plan view of the cover for footwear in the assembled configuration;

FIG. 8 is a bottom plan view of the cover for footwear in the assembled configuration;

FIG. 9 is an upper perspective view of the cover for footwear in the assembled configuration, showing the cover fitted over a shoe in broken lines and with the detachable pads in the assembled configuration; and,

FIG. 10 is another bottom perspective view of the cover for footwear in the disassembled configuration with broken lines showing unclaimed portions of the cover.

The cover for footwear shown in the figures is of the right foot, the left foot being a mirror image thereof.

The broken lines in the drawing views form no part of the claimed design.

1 Claim, 5 Drawing Sheets
